G. H. ROWE.
AUTOMATIC TIMER FOR STARTING ELEVATORS.
APPLICATION FILED AUG. 14, 1913.

1,230,434.

Patented June 19, 1917.

UNITED STATES PATENT OFFICE.

GEORGE H. ROWE, OF BERWYN, ILLINOIS, ASSIGNOR TO L. E. KING, OF BERWYN, ILLINOIS.

AUTOMATIC TIMER FOR STARTING ELEVATORS.

1,230,434.

Specification of Letters Patent. Patented June 19, 1917.

Application filed August 14, 1913. Serial No. 784,688.

To all whom it may concern:

Be it known that I, GEORGE H. ROWE, citizen of the United States, residing at Berwyn, in the county of Cook and State of Illinois, have invented a certain new and useful Improvement in Automatic Timers for Starting Elevators, of which the following is a full, clear, concise, and exact description.

10 My invention relates to automatic timers for starting elevators.

The object of my invention, generally speaking, is to provide means for automatically giving signals, both to ascend and descend, at regular, predetermined intervals, said means permitting adjustment of the time interval and of the relation of the ascending to the descending signals. My invention has as further contributory objects:

20 To provide a motor regulating resistance calibrated for definite time intervals;

To provide a plurality of mechanically actuated circuit-closing devices having improved means for adjusting the relative arrangement thereof to vary the sequence of the signals;

30 To provide manual adjusting means which may be mounted independently of the rest of the apparatus and hence located where it is readily accessible;

To provide a device which is simple, durable, efficient and in which the desired time intervals are maintained accurately for indefinite periods. Other objects and advantages will be apparent from the description hereinafter given.

In the accompanying drawings I have illustrated one embodiment of my invention which I have worked out in practice and 40 which has many advantages from a commercial standpoint. The invention may be embodied in other forms however.

Figure 1 is a plan view, partly in section, of the preferred construction.

45 Fig. 2 is a top plan view of the circuit-closing contacts;

Fig. 3 is an enlarged elevation of said contacts;

Fig. 4 is an elevation of the rheostat;

50 Fig. 5 is a circuit diagram showing one form of connections for the rheostat; and

Fig. 6 is a diagram showing a different form of connections therefor.

Fig. 7 is a diagram of a bank of elevators 55 provided with the timing devices.

The apparatus shown comprises, in the main, a motor driven gear train for rotating a pair of contacts to cause the latter to close two circuits periodically and an adjustable resistance for varying the speed of the motor. 60

The motor 1, which is of the shunt wound type, drives a suitable train of gears 2, 3, 4, 5, whereby a shaft 6 is rotated at a less rate than the armature shaft. The motor 65 and said gear train are inclosed within a suitable casing or housing 7 through which the shaft 6 projects. Said shaft is provided with a suitable collar 8 thereon which carries a resilient contact 9. Beyond said collar a disk 10 is arranged. A second collar 11 fits loosely over said shaft on the opposite side of said disk from said first collar and carries a second resilient contact 12. Said second collar is clamped in position by 70 means of a special cone-shaped nut 13, whereby the contact 12 may be arranged in any desired position angularly with respect to the contact 9. These rotating contacts are adapted to engage suitable stationary contacts 14, 15, respectively, thereby closing two circuits at regular intervals so as to give the desired signals to ascend and descend. Said contacts are mounted on a suitable support 16 preferably made of insulating material, said contacts being so arranged that each is engaged by its rotating contact without one interfering with the other in any manner. The two circuits may have a common return conductor connected to the 80 housing at the point 17, although the circuit connections may be effected in various other ways. A suitable circuit arrangement is shown in Fig. 2, in which current for actuating the bells B, B, when the circuits therefor are closed at the contacts 14 and 15, respectively, is supplied by the battery X. The said signals need not necessarily be produced by bells, as any suitable means for indicating to the operators that it is time 85 to begin the ascent or the descent, may be employed. Furthermore, the ascending and descending signals need not necessarily be produced by devices that are independent of each other structurally, as long as the indications are distinctive, so that the operators 90 will not confuse the ascending signal with the descending signal. For this purpose it is convenient to have separate signals such as illustrated herein, one located at or near 95

100 Fig. 2 is a top plan view of the circuit-closing contacts;

Fig. 3 is an enlarged elevation of said contacts;

Fig. 4 is an elevation of the rheostat;

Fig. 5 is a circuit diagram showing one form of connections for the rheostat; and

Fig. 6 is a diagram showing a different form of connections therefor.

Fig. 7 is a diagram of a bank of elevators 105 provided with the timing devices.

110

the top of the bank of elevators, and the other located at or near the bottom thereof.

As shown diagrammatically in Fig. 5, the motor comprises an armature 18 and a shunt field coil 19, the latter having in series therewith, the variable resistance 20 preferably of a sliding contact type, illustrated more fully in Fig. 4. The resistance wire, as is customary, is wound on a suitable support 21 from which it is insulated, said support being provided at opposite ends with suitable brackets or lugs 22 whereby the rheostat may be suitably mounted. A square rod 23 is carried by said brackets and supports a sliding block 24, the latter being provided with a pointer 25 which operates in conjunction with a graduated scale 26. Said scale is graduated to read directly in seconds, the proper graduations being obtained originally by calibration, whereby either of the circuits may be closed at regular predetermined intervals merely by adjusting the pointer to the position indicating the desired time interval. This adjustment varies the energization of the field windings, accompanied by a change in the speed of armature rotation, thereby varying the timing of the contact closers.

A switch 27 is provided whereby the supply circuit may be opened in adjusting the resistance. I find that this arrangement is desirable to prevent variations which would otherwise occur due to the residual magnetism of the motor. By opening said switch, however, the calibration of the resistance becomes definite due to the fact that the magnetism builds up from a minimum value to the desired value. It is obvious therefore, that in attaining this result, the switch need not necessarily be opened before the resistance is varied, although such order of operation is to be preferred as the operator is less liable to overlook the opening of said switch, than if he deferred the operation until after the resistance had been adjusted. In Fig. 5, where the resistance is in series with the field, the brushes 28 may be made of carbon, as is customarily done. In Fig. 6, wherein, as a modified arrangement, I have shown the resistance 20 connected in the armature circuit the brushes 29 are made preferably of copper. If made of carbon, the wide variations of current therethrough would cause changes in the resistance thereof which would destroy the accuracy of the timing device. With said resistance in the motor circuit, however, the switch above described may be omitted. In addition to the various arrangements described above, it is apparent that the gear ratio may be changed to give different calibrations, using motors having the same characteristics.

In Fig. 7 I have shown diagrammatically a bank of elevators 30 representing the floors

of a six story building, although the system is applicable to a building of any height, and in practice is usually applied to a modern office building much higher than a six story building. Four elevator cars 31 are illustrated, although obviously any number may be employed.

In practice the motor and the remaining parts associated directly therewith may be located in any suitable storage space, even though somewhat remote from the bank of elevators, for example, in the basement of a building. The resistance, being independent structurally of said motor, may be located in a convenient position near the foot of the bank of elevators as may also the switch, whereby the starter may adjust the pointer from time to time to accommodate the traffic which changes in volume during different hours of the day. The rotating contacts are not adjusted as often as the resistance. Said contacts are adjusted initially to meet the requirements of a given bank of elevators and thereafter their relation is practically fixed. Their initial adjustment depends on the height of the building, the speed of the elevators, the amount of traffic and the desirability of having the cars standing for a longer time at the bottom than at the top. For example, each car may be made to wait twenty seconds at the bottom but only ten seconds at the top, the greater time interval at the bottom being utilized in emptying and filling the car. In all prior devices with which I am familiar there is an equal interval of delay both at the top and the bottom, which equal intervals are objectionable as they do not permit the operation of the cars in the most efficient manner. A further advantage of my device is that the same standard equipment may be sold in substantially all cases for use under widely different conditions in different buildings. Since only a single ascending signal and a single descending signal are employed regardless of the number of elevators in a bank, no variation in the number of lamps or other signals is called for and no substitution of parts is required, as is the case with certain prior devices, but merely a simple adjustment of the parts of the standard equipment.

Although I have described the timing contacts as being adjustable by changing the rotating contacts, it is apparent that the adjustment may be otherwise effected. Furthermore, distinctive ascending and descending signals do not necessarily require two independent circuits, and therefore I do not limit myself to such plurality of circuits. Various other changes in the arrangement of parts and in the structural details may, of course, be made and in fact the invention may be embodied in various other forms with-

out departing from the spirit of the invention so long as said other forms or changes fall within the scope of the appended claims.

What I claim is:—

- 5 1. A signaling device for a plurality of elevators, comprising a distinctive signal for ascending and a distinctive signal for descending, one signal serving for all elevators in each case, means for operating 10 each of said signals at the same regular intervals, means for varying the length of said intervals, and means for varying the relative timing of the ascending and descending signals independently of the said adjustment of their timing interval.
- 15 2. A signaling device for elevators comprising two signals only, means for operating each of said signals at predetermined intervals in accordance with the number of 20 cars operating, and independent means for adjusting the period between the operation of one of said signals and the operation of the other of said signals to vary the relative periods of rest of said cars when reversing, 25 their direction of travel.
3. A signaling system for a plurality of elevators, comprising a single electrically actuated ascend signal, a single electrically actuated descend signal, circuits therefor, 30 means for periodically closing said circuits at intervals which may be varied to accord with the number of cars in use and means for adjusting the period between the operation of successive signals, to provide for 35 variation in the volume of traffic.
4. The combination with a bank of elevators, of a signal at the bottom of the bank for starting all the elevators upward at equal intervals, and a signal at the top of 40 the bank for starting all the elevators downward at the same equal intervals, a source of current having two parallel circuits therefrom in each of which one of said signals is included, a rotatable timing device and 45 coöperating contacts for closing said respective circuits, a shunt-wound motor for rotating said timing device, said motor op-
- erating with a weak field and having a resistance in the field circuit, a graduated scale calibrated to indicate time intervals, a 50 pointer associated with said scale and controlling said resistance, and a switch for opening the motor circuit concurrently with the adjustment of said resistance whereby when any new adjustment of the field strength is 55 made, the motor magnetization builds up from a minimum to the desired value, resulting in the same speed of armature rotation for successive adjustments to the same point on the scale, and insuring uniform timing of said elevators.
5. In a timing device for elevators, a pair of relatively fixed contacts, a pair of movable contacts, circuits therefor comprising signals, each of said movable contacts being 60 adapted to engage one of said fixed contacts to close a circuit, one of said circuits operating to give the signal to ascend and the other of said circuits operating to give the signals to descend, a shunt motor for driving said movable contacts, a variable resistance in the field circuit of said motor to control the timing of said signals and means permitting adjustment of the relative arrangements of the various contacts to vary 70 the relative periods of said ascending and descending signals.
6. In a device of the character described, the combination with a shunt-wound motor, of a variable resistance for determining the 80 speed of said motor, a scale associated with said resistance, said scale being graduated to indicate time intervals, timing signals operated by said motor and means for insuring a definite predetermined armature 85 speed for each and every variation of said resistance.

In witness whereof, I hereunto subscribe my name this 12th day of August, A. D., 1913.

GEORGE H. ROWE.
